ATTORNEY

UNITED STATES PATENT OFFICE

JOSEPH FEIGLESON, OF BROOKLYN, NEW YORK

CHANGEABLE SHIRT FRONT

Application filed September 6, 1928. Serial No. 304,243.

This invention relates generally to shirts and has more particular reference to a novel shirt front.

The invention has for an object the provision of a device of the class mentioned, which is of simple durable construction, desirable in use and efficient in action, and which can be manufactured and sold at a reasonable cost.

10 The invention proposes the use of a flat member divided on its front side into a plurality of sections, each section ornamented with a different shirt design, and said flat member being arranged for engaging upon a 15 button of a wearer's shirt for rotation for placing any of the sections on view between the opening of the wearer's vest or jacket. An advantage of this arrangement is that by mere rotation of the flat member it appears 20 as though the wearer has a different shirt on.

For further comprehension of the invention, and of the object and advantages thereof, reference will be had to the following description and accompanying drawings, and 25 to the appended claims in which the various novel features of the invention are more particularly set forth.

In the accompanying drawing forming a material part of this disclosure:—

30 Fig. 1 is a front fragmentary view of a person with the device applied.

Fig. 2 is a front elevational view of the device, per se.

35 Fig. 3 is an edge view thereof.

Fig. 4 is a fragmentary view similar to a portion of Fig. 2, but disclosing a modified form.

40 Fig. 5 is a view similar to Fig. 4, but disclosing a further modified form.

Fig. 6 is a sectional view, taken on the line 6—6 of Fig. 5.

45 Fig. 7 is a fragmentary view of the central portion of Fig. 2, but disclosing a modified construction thereof.

Fig. 8 is a similar view of a further modification.

The reference numeral 10 indicates generally a person wearing a shirt 10', a collar 11, a necktie 12, a vest 13, and a jacket 14. A 50 shirt front 15 constructed according to this invention is shown engaged beneath the necktie 12, and the vest 13, and partially beneath the collar 11. This shirt front is rotatively mounted as at 16 upon the button of the 55 wearer's shirt. This rotative mounting is accomplished by means of an aperture 17 formed in the shirt front 15.

The shirt front 15 consists of a circular flat member 18 formed on one side into a plurality of ornamented sections 19, each one of which simulates a different shirt. These sections are each segments of a circle.

In operation of the device the user merely has to turn the flat member 18 partially 65 around its pivot 16 for disposing a new segment of the flat member visible between the wearer's clothes, as shown in Fig. 1 for simulating a different shirt.

In the modified form of the device as shown 70 in Fig. 4, the flat member 18' is formed on its outer edge with concaved edge portions 20 extending along the edges of each of the segments 19. It is pointed out that these concave edges fit against the wearer's neck so as 75 to hold the flat member from accidentally turning. In this arrangement it is necessary to slightly bend the flat member before it may be turned to a new position.

In the modified form illustrated in Figs. 80 5 and 6, the shirt front consists of a rear backing 21 and a plurality of sections 22 simulating the different shirt fronts, sewed upon the front of the backing 21 by stitches 23.

85 In Fig. 7 the aperture 17 is shown connected with a plurality of slots 24, one slot for each section 19. Positioned on one side of these slots are eye members 25, and on the other sides complementary engageable 90

hook members 26. In operation of this shirt front, the aperture 17 is engaged upon the bottom of a shirt and then it is lowered or raised so that the threads holding the shirt button enter one of the slots 24. One hook member 26 may then be engaged in its eye member 25 for holding the device in position in its raised or lower condition. Each slot is provided with two pair of fastening members 25, 26, thus permitting various different vertical positions of the device as indicated by the small dot-dash circles 27 which indicate the threads of the shirt button.

In Fig. 8 another modified form has been shown in which the slots 24 connect with auxiliary bayonet slots 28. In this arrangement the device may assure various vertical positions by reason of the thread holding the shirt button upon which the device is mounted, engaging in any one of the bayonet slots 28.

While I have shown and described the preferred embodiment of my invention, it is to be understood that I do not limit myself to the precise construction herein disclosed and the right is reserved to all changes and modifications coming within the scope of the invention as defined in the appended claims.

Having thus described my invention, what I claim as new, and desire to secure by United States Letters Patent is:—

1. A shirt front, comprising a flat member having a central aperture for engagement upon a shirt button for rotative mounting, and ornamented sections arranged on one side thereof for simulating different shirt materials, and the edges of the flat member being formed into concaved portions extending individually across each of the said sections for engaging against a wearer's neck for holding the flat member against rotation.

2. A shirt front, comprising a circular flat member having a central aperture for engagement upon a shirt button for rotative mounting, ornamented sections arranged on one side thereof for simulating different shirt materials, and means for adjustably positioning the circular flat member in various raised or lowered positions relative to the support button.

3. A shirt front, comprising a circular flat member having a central aperture for engagement upon a shirt button for rotative mounting, ornamented sections arranged on one side thereof for simulating different shirt materials, and means for adjustably positioning the circular flat member in various raised or lowered positions relative to the support button, by reason of slots in the flat member communicating with the central aperture for engagement by the shirt button in raised or lowered positions of the flat member and an arrangement for holding the flat member engaged on the shirt button at points along the slots.

4. A shirt front, comprising a flat circular member having a central aperture for engagement upon a shirt button for rotative mounting, ornamented sections arranged on one side thereof for simulating different shirt materials, and said sections being sectors of the circular member for approximating the normally exposed portion of a shirt when worn by a person also wearing a jacket.

In testimony whereof I have affixed my signature.

JOSEPH FEIGLESON.
